UNITED STATES PATENT OFFICE

166,539

CHAIR

Willis K. Hutchason, Los Angeles, Calif.

Application December 24, 1951, Serial No. 17,813

Term of patent 14 years

(Cl. D15—1)

To all whom it may concern:

Be it known that I, Willis K. Hutchason, a citizen of the United States, residing in Los Angeles, in the county of Los Angeles and State of California, have invented a new, original, and ornamental Design for a Chair, of which the following is a specification, reference being had to the accompanying drawings, forming a part thereof:

I claim:

The ornamental design for a chair, as shown.

WILLIS K. HUTCHASON.
